UNITED STATES PATENT OFFICE.

ARTHUR J. MOXHAM, OF JOHNSTOWN, PENNSYLVANIA.

POCKET-FILLING DEVICE FOR GIRDER-RAILS.

SPECIFICATION forming part of Letters Patent No. 367,654, dated August 2, 1887.

Application filed March 11, 1887. Serial No. 230,564. (No model.)

To all whom it may concern:

Be it known that I, ARTHUR J. MOXHAM, of Johnstown, in the county of Cambria and State of Pennsylvania, have invented certain new and useful Pocket-Filling Devices for Girder-Rails, which invention is fully set forth and illustrated in the following specification and accompanying drawings.

The object of this invention is to provide a cheap filling for the side pockets of girder-rails, and thus to furnish a facing to which the ordinary or regular paving blocks or stones of the street may be set, which facing will prevent said paving from entering said pockets in case of settling down, or when said blocks or stones shall be worn down below the side trams of the rails.

The invention consists of a closing block-piece, either skeleton or solid, shaped to fill up the side pockets of the rail and form a flush or smooth vertical face for the paving stones to abut and hold securely in place, as herein-after particularly described.

In the accompanying drawings, Figure 1 shows a center bearing-rail, A, in cross-section, mounted on a box-chair, B, spiked to a cross tie, C.

The letters b indicate regular-shaped paving-blocks set as in the road-bed or street, and abutting and facing the pocket block-pieces D and E, fitted into each side pocket of the rail A.

One of the block-pieces D is shown detached and in perspective in Fig. 2. Said block-piece is of molded material—such as brick or blast-furnace slag—made in a short, solid piece.

Fig. 3 shows a longer piece, molded like piece D, except in greater lengths, and provided with projections or abutments e, which fit into the side pockets of the rail on the inner sides of the blocks, and thus, while presenting a smooth face on the outside, effect a saving of material over a solid block.

In Fig. 4 is shown a still further modification of the form and character of the block-piece or filling-piece (indicated by the letters G) within the pockets of the side bearing-rail, P. The other letters on said figure indicate like parts similarly lettered in Figs. 1, 2, and

3. Said block-pieces G are made of plate metal, shaped as shown in plan in Fig. 6, and

are bent, as shown on edge in Fig. 5, before insertion into the pockets of the rail, as seen in Fig. 4. A smooth or flush face is thus presented, as in the other cases, to the street-paving blocks b, by the metal box-pieces or skeleton blocks G.

This invention cheapens considerably the cost of paving the road-bed proper. In many places, while the ordinary street-paving stones are easily obtainable and cheap, it is nevertheless quite costly to obtain paving-blocks that are specially shaped for properly filling the pockets of the girder-rails of the railroad-track in such street. In such cases, instead of purchasing specially-made entire blocks shaped on one side to fit into the rail-pockets, the pockets can be filled with pieces of any of the forms hereinbefore described, specially made to fill up or cover only the pockets, and the rest of the paving can be laid with the cheaper regular paving blocks or stones at command.

In case of shipment of the metal block-pieces to distant points from the center of their manufacture, the saving in freight due to their lesser weight will largely exceed their greater original cost over the molded brick-pieces of greater weight.

I am aware that paving-blocks formed on one side to fit into the side pockets of girder-rails, as shown in Patent No. 360,780, issued April 5, 1887, have been heretofore proposed, and such I do not herein claim; but

As of my invention, I claim—

1. A pocket-closing block-piece shaped to close the side pockets of girder-rails and made substantially as described, whereby a facing to the pockets is provided for the support of the street-paving, substantially as set forth.

2. In combination with the paving of a street or road-bed having a railroad-track of girder-rails therein laid, filling-block pieces closing the side pockets of said rails and forming facings for supporting the pressure of said paving, substantially as and for the purposes set forth.

ARTHUR J. MOXHAM.
